CLAIM

The ornamental design for a vehicle taillight, as shown and described.

DESCRIPTION

FIG. 1 is a left side elevational view of a left vehicle taillight (the right vehicle taillight being a mirror image and is not shown);

FIG. 2 is a right side elevational view of the vehicle taillight;
FIG. 3 is a front elevational view of the vehicle taillight;
FIG. 4 is a top plan view of the vehicle taillight;
FIG. 5 is a bottom plan view of the vehicle taillight;
FIG. 6 is a perspective view of the vehicle taillight; and,
FIG. 7 is another perspective view of the vehicle taillight.
